UNITED STATES PATENT OFFICE.

HERMAN W. MARTIN, OF ILION, NEW YORK.

GAS-HEATER.

SPECIFICATION forming part of Letters Patent No. 792,715, dated June 20, 1905.

Application filed November 18, 1901. Serial No. 82,625.

To all whom it may concern:

Be it known that I, HERMAN W. MARTIN, a citizen of the United States, residing at Ilion, in the county of Herkimer and State of New York, have invented certain new and useful Improvements in Gas-Heaters, of which the following is a specification, reference being had therein to the accompanying drawings.

My invention relates to a gas-heater; and it consists in the mechanism herein more fully described and claimed.

The purpose of my invention is to provide an improved method of heating by gas and other fuel, which will be hereinafter more fully pointed out and claimed.

In the drawings, Figure 1 represents a front view of my heater, broken lines indicating parts removed. Fig. 2 is a side elevation of Fig. 1, a sponge and sponge-holder being also shown in section-lines. Fig. 3 is a plan view of the heater. Fig. 4 is a section taken in the plane of the line A B, Fig. 1. Fig. 5 is a top view of the gas-heater. Fig. 6 is a reversed view of Fig. 5.

Having described my invention in reference to the figures illustrated in the drawings, I will now proceed to describe the same in detail, in which similar numerical references will refer to corresponding parts in the several views.

I preferably provide wall-bracket 1, provided at its top with opening 2 for sustaining the same on the wall, which carries at its opposite end bracket or stand 3, which may or may not be provided with legs 4. In this instance I provide supporting-brackets 5 5, which are secured to back wall and bracket 1 for supporting thereon liquid-tank 6, which in this instance is provided with tube 7, 40 through which the liquid is free to descend into a sealed heating-tank 8. For securing circulation and preventing explosion I provide circulating-tube 9, which enters the wall of the tank at 10 and is connected at 11 with the sealed heating-tank at its edge or side. By this arrangement a continuous circulation of liquids may be maintained through the fluid-tank and the sealed heating-tank, and thereby prevent explosion which might occur 50 by producing an excess of heat in the sealed

heating-tank, which would drive the liquid up through pipe 7, and thereby produce an explosion.

The sealed heating-tank is supported below the liquid-tank 6 and above stand 3 and is so arranged that the liquid will flow into the sealed heating-tank by gravity. Beneath the sealed heating-tank I provide a gas-burner 12, which I illustrate as consisting of the perforated metal disk 13, which forms its upper 60 surface. Beneath this disk 13 I provide a second disk 14, which is also perforated and which is secured to the upper disk by a collar 15, connecting the two, which collar may be formed by turning up the edge of the disk. The gas 65 is fed through tube 16 into the space between the disks, where it passes through the perforation in the upper disk and there is burned, the perforations in the lower disk being provided for the admission of air to mix with the 70 gas. Tube 16 is provided to supply the gas and is bent, as shown in Fig. 6, to form a seat or base for the gas-burning portion of my device.

For admitting air into the gas I provide 75 transverse tube 18, which is open at both ends to admit the air and permit the same to be mixed with the gas as it passes from the gas-supply into the convoluted tube located under the perforated burner 12, and by admitting air 80 through perforated bottom 13 under the perforated burner a sufficient supply of air is mixed with the gas to produce the requisite quantity of heat.

Gas-supply pipe 19 passes through the tube 85 18 and a flow of gas therein is controlled by the stop-cock 20 (illustrated in Fig. 1) by permitting the screw-threaded stop-cock to enter the wall of the gas-supply pipe for regulating the flow of the gas into the burner, the gas 90 being permitted to pass through the end of the gas-pipe.

By locating burner 12 under sealed heating-tank 8, so that the heat generated by the burner is carried against the under side of the 95 sealed heating-tank 8, the required degree of heat can be obtained at a nominal expense.

The stand 3 is provided with an opening of a radially-slotted outline, as at 26, (shown in Fig. 4,) to permit the heated air to come into 100

contact with the sealed heating-tank. I illustrate this opening in the general form of radial fingers, which offer a radiating-surface.

For using the gas-burner for heating and 5 other purposes I provide the usual heating-plate 21, (best illustrated in Fig. 4,) which may be either integral with or independent of bracket or bottom 3.

For supplying the heated liquid to the surface which may be required to be cleansed I provide outlet-pipe 22, which is controlled by stop-cock 23, which is attached to receiving-flange 25, in which I insert sponge 27 or other fibrous material, so that the heated liquid 15 passes through opening 28 into the sponge or other fibrous substance, so that with a small quantity of heated liquid a warm sponge-bath may be taken. By the continuous flow of heated liquid through the sponge or other fibrous substance, and at the same time that the 20 sponge or other fibrous substance may be replaced from time to time, in consequence of this operation the sponge or other fibrous sub-

stance is kept clean by the continuous outflow of the liquid through the same.

What I claim as new, and desire to secure by Letters Patent, is—

In combination, an integral stand having a standard and a base portion, said latter comprising a heating-plate formed with a central 30 heat-directing opening and with slots radiating from said central opening, a burner beneath the heating-plate, supporting-arms fixed to the standard, a liquid-tank resting upon said arms, a heating-chamber in open communication with and supported solely by the tank immediately above the heat-directing opening in the plate, and an outlet-tube from the heating-chamber.

In testimony whereof I affix my signature in 40 presence of two witnesses.

HERMAN W. MARTIN.
